Patented Apr. 18, 1916.

FIG. 4

FIG. 3

FIG. 5

INVENTOR.

Ralph H. Whitcomb

UNITED STATES PATENT OFFICE.

RALPH H. WHITCOMB, OF AMHERST, MASSACHUSETTS.

SPRING-RELEASE DEVICE.

1,179,590.

Specification of Letters Patent. Patented Apr. 18, 1916.

Application filed June 15, 1915. Serial No. 34,251.

To all whom it may concern:

Be it known that I, RALPH H. WHITCOMB, a citizen of the United States, residing in Amherst, in the county of Hampshire and 5 State of Massachusetts, have invented new and useful Improvements in Spring-Release Devices, of which the following is a specification.

My invention relates especially to spring 10 release devices and its employment in a tail holding and other analogous devices.

The object of my invention is to provide a simple, inexpensive and effective device by the employment of which an object, such for 15 instance, as a cow's tail, may be held out of the way of the milker and with which if superior strain be exerted, caused for instance, by the cow's lying down, the holding member will be automatically released, thus 20 precluding the possibility of injury to the animal.

It has the further object of providing 25 means for changing the tension required to release the holding member permitting adjustments to suit varying conditions.

In the drawings I illustrate the construction of my device and show it as employed as a part of a cow tail holder.

In the drawings similar numerals indicate 30 like parts through the several figures.

Figure 1 illustrates the device on a small scale and arranged as employed as a cow tail holder. Fig. 2 is a side view of the holder showing two latches of different shape, both 35 pivotally mounted on the spring. Fig. 3 is a top view of the same. Fig. 4 illustrates a modification in which three latches or releasing members are employed, each being of different length, and Fig. 5 illustrates a 40 modification wherein means is provided for varying the tension required to release the latch.

The construction and operation of my device will be readily understood on reference 45 to the drawings.

In each of the different forms illustrated it will be seen the latch is pivotally or loosely mounted on, or connected with the spring, so that when the spring is extended a pre- 50 determined distance the latch escapes from the eye 8 allowing the ring 5 to escape from the latch. It will readily be seen that two or more latches may be mounted on a single spring and that latches of various shapes 55 and forms may be employed.

In Fig. 2, I illustrate the spring with two

latches mounted thereon, the one on the right of the figure being adapted to receive the ring without the necessity of the latch being released from the eye 8, while that on 60 the left requires that the latch be moved out of the eye 8 before the ring 5 is mounted thereon. In Fig. 4 I illustrate a like construction excepting that the latches are all of the simplest type and are of different 65 lengths so that if greater strain is desirable before the releasing of the ring, then the longest latch is employed. The device will then of course not operate to release the latch until the spring has been extended a 70 greater distance than would be the case if the shorter latch were employed.

In Fig. 5 I illustrate a modification wherein any type of latch may be employed but where the varying tension or strain required to release the latch is attained by the employment of adjusting means resulting in extending the free end of the latch a greater or less distance through the holding eye 8, and as one means to conveniently provide for such adjustment I illustrate the eye provided threaded member 10 in engagement with the spring and having mounted on the threaded portion the lower end of the latch 4, the same being held in position by 80 one or more nuts 11, 12. It will be seen that with this construction when strain is applied on the cord 6, the latch will be drawn downwardly thus extending the spring and at the same time the threaded member 10 will turn 85 on its hook connection with the lower part of the spring until the spring has been opened sufficiently to allow the free end of the latch to escape from the eye 8 and it will be readily seen that the tension required in 90 order to accomplish the release of the latch may be varied by moving the nuts up or down on the member 10.

It will readily be seen that without material change springs of other types and that 100 latches and pivotal connections of various kinds may be employed without departure from my invention.

For the purposes of convenience in placing the latch in the eye 8 and to avoid the 105 necessity of extending the spring and projecting the latch longitudinally through the eye 8, I prefer that this eye be formed so that the latch will just pass laterally through the opening into the eye 8 as illustrated in Fig. 3.

Having therefore described my invention,

what I claim as new and desire to secure by Letters Patent is:—

1. In a device of the character described, the combination of a spring adapted to be supported and having a latch supporting extension, a latch engaging eye and a latch loosely mounted on the spring extension and arranged to engage the eye, and adapted to be released at a predetermined point when the spring is put under the requisite tension.
2. In a device of the character described, the combination of a spring, an extension pivotally attached thereto, a latch adjustably mounted on the extension and an eye to be engaged by the latch.
3. The combination in a device of the character described of a spring, an eye integral therewith and a latch pivotally

mounted on the spring at the opposite end, and adapted to engage said eye. 20

4. In a device of the character described, a spring, an eye, and a latch adapted to engage the eye and to move laterally away therefrom when released and adjustably mounted on a member supported by the spring, whereby the latch may be moved toward or from the spring thus controlling its extent of projection through the eye. 25

5. The combination in a device of the character described of a coiled expanding spring, a latch engaging eye, and a latch pivotally mounted on the spring, whereby when the spring is opened a predetermined distance the latch escapes from the eye. 30

RALPH H. WHITCOMB.
